UNITED STATES PATENT OFFICE.

JAMES S. STEWART, OF NEW YORK, N. Y.

ROTARY SNAP-SWITCH.

1,171,987.

Specification of Letters Patent. Patented Feb. 15, 1916.

Application filed December 2, 1913. Serial No. 804,278.

To all whom it may concern:

Be it known that I, JAMES S. STEWART, a citizen of the United States, residing at the city of New York, in the borough of Manhattan and State of New York, have invented certain new and useful Improvements in Rotary Snap-Switches, of which the following is a full, clear, and exact description.

10 This invention relates to rotary snap switches and is designed primarily for use with electric lamps, constituting a type of switch, commonly known as "pull sockets", in which the circuit controlling mechanism 15 is actuated by a cord or chain depending from the lamp socket.

One object of my invention is to provide a switch which is composed of a comparatively few number of parts of a simple construction, arranged in compact form in an insulating body which completely houses them.

Another object of my invention contemplates an arrangement of the parts of the 25 circuit controller in which the elements constituting the circuit connections are not subjected to the strains resulting from the pull on the chain, whereby the danger of the circuit controller becoming easily broken or 30 getting out of order is substantially eliminated.

With these and other objects which will in part be obvious to those skilled in the art and will in part be hereinafter set out, my 35 invention consists of novel parts, constructions, combinations and improvements herein shown and described and particularly pointed out in the appended claims.

In the drawings: Figure 1 is an elevation 40 of a complete lamp socket embodying my invention, a portion of the inclosing shell being removed to more clearly show the socket; Fig. 2 is a view of the bottom of the base of the socket with the threaded shell removed to show the spring detent; Fig. 3 is 45 a plan of the top of the base of the socket, the cap being removed to show the circuit controlling mechanism; Fig. 4 is a vertical section of the socket on the line 4-4 of Fig. 1; Fig. 5 is a vertical section on the line 5-5 of Fig. 3; Fig. 6 is an end view of the drum of the circuit controller looking toward the left in Fig. 3, the detent co-acting therewith being shown in dotted lines; 50 and Fig. 7 is a detail view of the end face of the drum and the pawl in the position

they assume after the chain has been released.

The body of the socket comprises a base 1 and a cap 2, each consisting of substantially 60 cylindrically shaped blocks of porcelain or other suitable insulating material which are fastened together by bolts 3, passing through the base and cap respectively, and screwing into nuts 4, fitted into recesses in the cap 2. 65 The nuts and recesses are preferably made non-circular to facilitate in assembling as the nuts may be placed within the recesses and thus prevented from turning while the bolts are threaded into them. The cap and 70 base are each provided with recesses which form a cylindrically-shaped chamber in which is arranged a circuit controller drum 6. On the periphery of the drum 6 adjacent one of its ends are ratchet teeth 7, which in 75 the usual construction of the drum are four in number, but any even number of teeth may be used. Contact plates 8 are fastened to one face of alternate teeth, which faces are diametrically opposite each other and a 80 metallic band 9 fitting in a suitable recess in the end face of the drum connects these two contact plates together. Mounted on the band 9 coaxially with the axis of the drum is a pintle 10, the contact plates 8, the band 85 9 and the pintle 10 forming part of the circuit connection and will be hereinafter referred to. The pintle 10 rests in a groove or bearing formed in the base 1, while the abutting face of the cap 2 forms the other 90 portion of the bearing when the socket is assembled. The other end of the drum 6 is rotatably supported on a stationary shaft 11, one end of which fits into a longitudinal cylindrical recess in the drum arranged coaxially with the axis thereof. One end 12 of the shaft 11, is bent at right angles to the main portion thereof and extends into a cylindrical recess 12' formed in the base 1. The portion of the base between this recess 95 and the chamber for the drum has a groove 10, which forms a seat for the shaft 11 and prevents any lateral movement thereof.

The drum 6 and associated parts, together with terminal plates comprise the circuit 105 connections whereby current is supplied to the lamp as will now be described. Mounted in a rectangular recess in the exterior cylindrical wall of both the cap and base, is a rectangularly-shaped terminal plate 13, the 110 upper end of which has an offset piece 14 provided with a threaded opening into

which is threaded a screw 15 mounted in a recess in the cap 2, which securely fastens the plate to the cap. One side of the plate 14 is slightly offset and carries a binding post 15' to which one of the supply conductors (not shown) is fastened, the cap 1 being provided with a suitable groove 17, for the supply conductor which passes down between the socket and the exterior shell. To 10 the other side of the plate 13, is attached a lug 18 preferably integral therewith which lug is bent over to a position in parallelism with the plate and preferably spaced a slight distance therefrom. The flat portion 15 of the lug 18 is opposite a circular opening 19 in the plate 13 in which the pintle 10 is rotatably supported, the lug forming an end thrust plate against which the end of the pintle is held in good electrical contact by 20 means which will hereinafter be referred to.

The bottom of the base is divided into two substantially segmental-shaped surfaces 20 and 21, the surface 20 having a rectangular portion 22 projecting therefrom and centrally disposed with respect to the socket, the segmental-shaped surface 20 and the projecting part of 22 being raised sufficiently above the plane of the surface 21 so that the central contact which will be hereinafter described, will alone contact with the center contact of the lamp bulb in accordance with the ordinary construction of lamp sockets.

A rectangular slot 24 leads from the surface 21 to the semi-cylindrical chamber in the base 1. Projecting into this slot is a spring detent 25 which consists of a flat plate adapted to rest against the segmental shaped surface 21, the plate having formed integral therewith, a spring or contact blade 27, which is adapted to engage with the teeth 7, and the contact surfaces 8.

The flat plate of the spring detent 25 is maintained in position against the base 1 by a metallic shell 28 which forms a part of the electric circuit and which is closed on one end, the closed end being cut away to permit the shell to rest on the segmental shaped surface 21, and to prevent electrical contact with the center contact which will hereinafter be referred to. The shell 28 is threaded to form a socket into which the lamp bulb is screwed as in the usual construction and forms one terminal of the 55 lamp.

The shell 28 and detent 25 are held in place on the base by the bolts 3 which pass through openings in the shell and detent plate respectively.

60 The other supply conductor (not shown) is carried down inside of an exterior shell in a recess 29 formed in the peripheral walls of the cap and base and the conductor is fastened to a terminal plate 30 having an 65 offset piece 31 fitting in the recess 29, pro-

vided with the usual binding screw 32. The main portion of the plate 30 is substantially T-shaped, the long arm fitting into the recess in the segmental shaped surface 20, in which it is held by a screw 33 mounted in a recess in the base 1. The short arm 34 rests on the face of the projecting portion 22 and constitutes the central contact, which is adapted to engage with the center contact of the lamp (not shown) and forms the 75 other terminal of the lamp.

Ratchet teeth 35 are cut on one of the end faces of the drum, which teeth are equal in number to the number of teeth 7. The particular formation of these teeth form one of the important features of the invention and as shown they do not extend to the recess in which the shaft 11 fits but to an annular boss 36 formed on the end face of the drum which boss surrounds the recess referred to. The faces of the teeth 35 are inclined to a plane perpendicular to the axis of the drum while the edges of the teeth lie substantially in this plane, with the boss 36 projecting slightly beyond it. A pawl 37 bent at its 80 upper end to engage the teeth 35 is provided with an opening 39 of larger diameter than the shaft 11 which passes therethrough to permit the pawl to rock or tilt as well as to rotate thereon, the annular boss 36 having a rounded surface against which the pawl 37 bears to normally prevent the pawl from being pressed into firm engagement with the teeth 35 and acting as a fulcrum on which the pawl can tilt as will be clear from the 85 operation of the device. The pawl 37 is provided with an offset ear 38 projecting from the upper end of the pawl.

A pull chain 40 is attached to the ear 38 by passing the filament between the two end beads of the chain, through a slot in the ear, the cup-shaped ear forming a seat for the end bead. A coiled spring 42 is mounted on a shaft 12 and in the groove 10', one end thereof being fixed in the recess alongside the bent end 12 of the shaft, while the other end of the spring engages with the offset ear 38 and rests against the pull chain 40 to hold the same securely attached to the pawl. The end coil or convolution of the spring 42 abuts against the end of the groove 10' and exerts a pressure on the drum to maintain the pintle 10 against the lug 18. This spring serves four functions; first, by its engagement with the pawl 37, it maintains it under a torsional stress, so that after a pull on the chain 40, the pawl will return to a position against a shoulder 44 on the face of the base 1 (see Fig. 4); second, it holds the pawl 37 against the boss 36 of the drum and thus maintains the pawl in loose engagement with the teeth 35; third, the spring exerts its tension to continually urge the drum 6 and the pintle 10 against the lug 18, carried by the terminal plate 13 to maintain these parts in 100 105 110 115 120 125 130

good electrical contact; and, fourth, it holds the pull chain 40 securely attached to the pawl 37.

The abutting faces of the cap and base 5 have semi-circular grooves 45 therein, which extend from the chamber for the circuit controller to the exterior of the walls, providing a cylindrical passageway through which the pull chain 40 extends to the exterior of 10 the socket. This passageway is at an angle to a line perpendicular to the axis of the drum for a purpose which will be later referred to. Non-circular recesses 46 are cut in the grooves 45 adjacent the peripheral walls 15 of the cap and base and a metallic bell or funnel 47 provided with flanges 48 corresponding in shape to the non-circular recesses 46 is held securely in place therein when the cap and base sections are united. 20 This manner of securing the bell or funnel in place provides a simple, and convenient construction, which facilitates the assembling of the socket.

The completed socket is inclosed in the 25 usual exterior shell comprising a body portion 49 and a cap 50 which are locked together by any form of a locking joint, the body portion 49 being provided with a slot in which the bell or funnel 47 rests.

30 To assemble the socket, the terminal plate 30 is first secured to the base 1. The drum 6, shaft 11, spring 42 and pawl 37 to which the pull chain 40 has been attached, are separately assembled and then placed in the 35 chamber in the base 1, one end of the spring 42 and the bent end 12 of the shaft 11 fitting in the recess 12' in the base. The other end of the spring 42 is then fastened over the offset ear 38 which will maintain 40 the pawl 37 under tension. The spring detent 25 and the shell 28 are then placed in position on the segmental-shaped surface 21 and the cap and base portions united by the bolts 3. However, before uniting the cap 45 and base portions, the funnel 47 is placed in the recesses in the abutting faces of these portions and when the cap and base sections are united, will be held in place. Finally, the terminal plate 13 is fastened to the cap 50 by the screw 15. The recesses in the base and cap are then filled with cement in the usual manner, the conductors attached to the terminal plates and the exterior shell placed over the complete socket.

55 The pawl 37, when the parts are assembled in this manner, will be held against the boss 36 and will be prevented from pressing against the faces of the teeth 35 by the spring 42 and due to the torsional 60 force of this spring the pawl will be forced against the shoulder 44 on the face of the base (see Fig. 3). If the chain 40 is now pulley to actuate the circuit controller, the force will not be directed perpendicular to 65 the axis of the shaft 12 since the grooves

45 and the bell or funnel 47 through which the chain passes are at an angle thereto. The pull will therefore have a component tending to pull the end of the pawl 37, to which this chain is attached toward the 70 teeth 35. The pawl will therefore be rocked on the rounded surface of the boss 36 which will permit the upper end of the pawl to firmly engage with one of the teeth 35. This movement of the pawl is facilitated 75 by the arrangement of the offset ear 38 for since this ear projects laterally from the upper end of the pawl, the angle at which the pull chain lies with respect to the plane perpendicular to the axis of the drum is 80 increased. The lower end of the pawl will also be forced laterally with respect to the shaft 12, against the tension of the spring 42, but this tension will not be sufficient to prevent the engagement of the pawl with 85 the teeth 35, and the drum will be rotated. At the end of the pull, the pawl 37 and chain 40 are in alinement. It is in this position that the strains resulting from too strong a pull on the chain will be imparted 90 to the circuit controller, but since the pawl and chain are in alinement, the stress of the pull will occur entirely on these parts and the shaft 11 which is seated in the groove 10' is prevented from lateral movement, so that it will take the brunt of the 95 pull. It will therefore be seen that the stress resulting from the pull does not occur on the drum 6, the spring detent 25 or any of the parts which carry the current. When 100 the drum has been carried to this position by the pawl 37 the spring detent 25 will snap into engagement with one of the teeth 7 and if the blade 26 is in contact with one of the contact surfaces 8, the circuit will be 105 completed to the lamp as follows; terminal plate 13, plug 18, pindle 10, contact surface 8, detent 25, shell 28, which forms one terminal of the lamp through the lanip to center contact 34 and terminal plate 30 to the other conductor, when the detent 25 is in engagement with alternate teeth, the circuit will be broken between contact surface 8 and the detent. If the chain 40 is now 110 released, the spring 42 will again exert its 115 force against the pawl 37, to press the same against the boss 36, and withdraw the bent end of the pawl from frictional engagement with one of the inclined faces of the teeth 35 (see Fig. 7). The torsion of the spring 120 will then return the pawl 37 to its normal position against the shoulder 44, with comparatively little frictional contact between the pawl and the inclined faces of the teeth on the drum for as the pawl returns to its 125 normal position, the bent end of the pawl will engage only with the point of the tooth. The strength of the spring necessary to return the pawl to its original position when teeth 35 are of the construction de- 130

scribed, is much less than the strength of the spring required to return the pawl to its normal position where the pawl rides over the inclined surfaces of the teeth and for this reason, I find the above described construction preferable, as one of the essential features of pull sockets of this type is to provide a construction in which the lamp socket may be readily manipulated 10 with a slight pull on the chain.

While I have illustrated and described the rotary snap switch in combination with a pull socket yet it is not my intention to limit the invention to this particular type 15 of switch as the drum circuit controller and actuating mechanism are equally applicable to other types of switches where the pawl 37 may be actuated by a push rod instead of a pull chain and it is my intention to 20 be limited only to the scope of the claims appended hereto.

Having thus described my invention, I claim:—

1. In a pull socket, the combination with 25 a drum circuit controller having spaced contacts thereon and a shaft electrically connected to said contacts, of a terminal plate having an aperture therein and a lug extending from said plate opposite said aperture, said shaft passing through said aperture, and means for holding said shaft against said lug to maintain them in electrical contact.

2. In a rotary snap switch, in combination, a body having a chamber therein, a drum controller in said chamber having spaced contacts thereon, a shaft electrically connected with said contacts for rotatably supporting one end of said drum, a second 40 stationary shaft for rotatably supporting the other end of said drum, said shaft having a bent portion inserted in a recess in said body, a terminal plate on said body against which said first named shaft abuts, 45 ratchet teeth on said drum, a pawl mounted on said second named shaft for engagement with said ratchet teeth and a coiled spring on said second named shaft, having one end inserted in said recess, and the other end 50 engaging with said pawl, for maintaining said pawl under tension and for forcing said first named shaft against said terminal plate.

3. In a rotary snap switch, a circuit controller having a shaft forming part of the circuit connection, a terminal plate having an aperture therein through which said shaft passes, said plate having a lug against which said shaft abuts to maintain electrical contact between the parts and means on said plate for securing thereto a conductor wire.

4. In a pull socket, the combination with 65 a body having a chamber therein, a drum circuit controller in said chamber, a shaft

for rotatably supporting the same, ratchet teeth on one end face of the said drum, a boss on said face projecting beyond the plane of said teeth, a pawl loosely mounted on said shaft bearing against said boss, a 70 coiled spring on said shaft bearing against said pawl, and a pull chain attached to said pawl passing through an opening in said drum, said opening being arranged at an angle to the face of the drum. 75

5. In a pull socket, in combination with a body having a chamber therein of a drum circuit controller in said chamber, a shaft for rotatably supporting one end of said drum, ratchet teeth formed on one end face 80 of said drum, a pawl loosely mounted on said shaft, means including a part projecting from the face of said drum normally holding said pawl out of frictional engagement with the inclined faces of said teeth 85 and means including a pull chain for tilting said pawl into engagement with said teeth upon the pulling of the chain.

6. In a pull socket, a body of insulating material having a chamber therein, a terminal plate secured to the exterior of said body, a drum controller in said chamber having spaced contacts thereon in electrical connection with said terminal plate, a plate mounted on the bottom of said body having 90 a contact blade integral therewith extending through an opening in said body and coacting with the spaced contacts on said drum, a threaded lamp socket secured to the bottom of said body and holding said plate 95 in place, said socket resting against and in electrical contact with said plate, a second terminal plate on said body, said body having a projecting lug, said shell having a recess therein through which said lug projects, 100 said last named terminal plate having a portion thereof resting on said lug and out of contact with said socket and forming the center contact for the lamp. 105

7. In a rotary snap switch, in combination, a body comprising head and base portions having recesses therein forming a chamber, a drum circuit controller therein comprising a body of insulating material and spaced contacts on said drum, a shaft 110 electrically connected to said contacts for supporting one end of said drum and a stationary shaft having one end fitting into a central recess in said drum for supporting the other end thereof, said last named shaft 115 having its other end bent and fitting into a recess in said base portion, the head portion of said body bearing upon the shaft to maintain it in said recess.

8. In a rotary snap switch, in combination, a body having a chamber therein, a controller drum in said chamber having spaced contacts thereon, a shaft electrically connected to said contacts and passing through an aperture in said body, a termi- 120 125 130

nal plate on the exterior of said body having a seat for the end of said shaft and against which said shaft abuts and means for supporting the other end of said drum and for 5 forcing said first named shaft into electrical contact with said terminal plate.

9. In a rotary snap switch, the combination with a body and chamber therein, of a drum circuit controller in said chamber, a 10 shaft for rotatably supporting said drum, ratchet teeth formed on one end face of said drum, a pawl loosely mounted on said shaft and adapted to engage said ratchet teeth, means including a part projecting from the 15 face of said drum for holding said pawl out of frictional engagement with said teeth, and means including a member extending exteriorly of said body for tilting said pawl into engagement with said teeth.

10. In a rotary snap switch, the combina- 20

tion with a body having a chamber therein, of a drum circuit controller in said chamber, a shaft for rotatably supporting the same, ratchet teeth on one end face of said drum, a boss on said face projecting beyond the 25 plane of said teeth, a pawl loosely mounted on said shaft, a coil spring surrounding said shaft and connected to said pawl for forcing it into engagement with said boss and exerting a tension thereon, and a member 30 attached to said pawl extending to the exterior of said drum for tilting said pawl into engagement with said teeth and rotating it against the tension of said spring.

In witness whereof, I subscribe my signature, in the presence of two witnesses.

JAMES S. STEWART.
